CLAIM

The ornamental design for a packaging container for a shirt or the like, substantially as shown and described.

DESCRIPTION

FIG. 1 is a front elevational view of a packaging container for a shirt or the like, showing my new design; FIG. 2 is a side view thereof, without the label insert of the lower portion; and, FIG. 3 is a rear elevational view thereof. The broken lines in FIGS. 1 and 3 are for the purpose of showing environmental use only.
